MAX C. BATSEL, OF WILKINSBURG, PENNSYLVANIA.

INTERTUBE TRANSFORMER FOR VACUUM-TUBE AMPLIFIERS.

Application filed March 5, 1921. Serial No. 449,611.

This invention relates to the coupling of 5 transformers and more particularly to the coupling of transformers for connecting vacuum tubes in cascade for the amplification of radio signals of either audio or radio frequency, and my invention has equal application both to radio telephony and telegraphy.

In coupling transformers, the amplification of potential varies directly as the ratio 10 of the number of turns in the primary to the number of turns in the secondary. The greatest amplification possible, therefore, takes place when the maximum number of 15 turns are used in the secondary. This means that the number of turns of the secondary of the transformer; i. e., the inductance in the grid-filament circuit of the amplifier tubes, should be the maximum. 20 The maximum practicable number of turns in the grid-filament circuit that forms the secondary of the transformer is that number of turns which brings that circuit into resonance with the average operating frequency.

Heretofore, it has been considered impossible to utilize a resonant grid-filament circuit in the amplifier tubes for the reason that, at the resonant frequency, the tuned 30 grid-filament circuit operates as capacitance conductively coupled in parallel to the inductance of the primary of the transformer; i. e., the inductance in the plate-filament circuit of the tube supplying the oscillations. 35 The effective value of the capacitance was such that the inductance of the primary winding with this effective capacitance was resonant at some frequency. By reason of this phenomenon, the maximum number of 40 turns in the secondary or that number at which the secondary is resonant to the operating frequency has never been employed and maximum possible amplification has never been obtained.

45 My invention comprises the use of a secondary or grid-filament circuit tuned to the average operating frequency. This means that the maximum number of turns will be present in the secondary of the transformer, and hence, the maximum amplification possible will be obtained. To flatten out the impedance-frequency curve for the primary of the transformer, I employ an inductance in the plate-filament circuit of large value, in 50 proportion to the rest of the impedance in

said circuit. This gives, for the low frequencies, a large value to the impedance in the primary circuit, hence an increase of the impedance at resonant frequencies does not produce an objectionable change in the effective amount of impedance in the primary circuit.

An object of my invention is to get the maximum number of turns in the secondary in intertube transformers for connecting 65 vacuum tubes in the amplification of radio signals.

Another object is to get the maximum number of turns in the secondary of a transformer, in such circuit, without objectionable excessive variations in the impedance of the primary circuit at different frequencies.

With these and other objects in view, the invention consists in the parts and combinations to be hereinafter explained, with the 75 understanding that the several necessary elements may be varied in proportion and arrangement without departing from the spirit of the invention.

In the drawings, Figure 1 illustrates diagrammatically a receiving system in which vacuum tubes, coupled according to my invention, are cascaded to amplify received signals.

Fig. 2 illustrates diagrammatically the 85 equivalent circuit of an intertube transformer for determining the primary impedance.

Fig. 3 is a diagram showing the variation of current values with frequency where inductance and capacity are connected in parallel.

Fig. 4 is a diagram showing graphically the variation of impedance with frequency in the primary of an intertube transformer.

Referring to the drawing, in Fig. 1 is shown an antenna circuit comprising an antenna 1, an inductance 2 and a variable capacitance 3 through which the circuit is connected to ground. By varying the variable 95 capacitance 3, the circuit may be tuned to any frequency desired. Inductively coupled to the inductance 2 is an inductance 4 in the grid circuit of a three-electrode vacuum tube 5 operating as an amplifier. Connected in 100 parallel with the inductance 4 is a variable capacitance 6, permitting the circuit to be tuned to any desired frequency. Connected to the inductance 4 is a grid 7 of the electron tube 5. The inductance 4 is likewise con- 110

nected to a filament element 10 of the electron tube 5 which is heated by a suitable battery 11.

The plate circuit of the vacuum tube 5 comprises a plate element 12, a plate or "B" battery 13 and an inductance 14. The inductance 14 performs the function of the primary of an intertube transformer. The inductance 14 is of relatively high value, in proportion to the rest of the impedance in the plate circuit of the vacuum tube 5. The impedance Z_p in Fig. 2 shows the equivalent circuit for the primary of the intertube transformer. The impedance Z_p has a higher impedance for a broader band of frequencies as the ratio of inductance to capacitance is increased. The capacitance in this primary circuit is the capacitance of the grid-filament circuit of a tube and comprises the capacitance between the filament and the grid and the distributed capacitance of the winding.

The greater the number of turns in the primary, the greater the ratio, therefore, of inductance to capacitance. Since the voltage acting in the plate-filament circuit divides between the two impedances in direct ratio to the value of each, the larger the value of impedance Z_p the greater the value of voltage acting upon the primary of the intertube transformer. To have a large voltage acting upon the primary is desirable but there is a point, which can be easily determined, beyond which increase in the number of turns in the primary is not advantageous. The reason for this lies in the fact that the amplification in the transformer depends upon the ratio of the number of turns of the primary to the number of turns of the secondary. There is another feature which must be taken into consideration, namely, the proper value of impedance Z_p to obtain a suitable flattening of the impedance curve to enable my system to be used in telephony. A discussion of this question will be later fully dealt with.

The computation of the impedance Z_p may easily be made from an inspection of the equivalent circuit shown in Fig. 2. In this figure of the drawings, R_o represents the internal impedance of the plate circuit and Z_p the impedance of the transformer primary. C is the distributed capacitance of the winding plus the capacitance of the grid-filament circuit of the next vacuum tube in the cascade. The impedance of this primary winding, considered alone, may be represented by the following equation:

$$60 \quad Z_p = \sqrt{R_p^2 + (fL_p)^2}$$

where R_p is the resistance of the primary; f represents the frequency; and L_p is the inductance of the primary.

Inductively coupled, through an iron core, to the inductance 14, is an inductance 15 in

the grid-filament circuit of an electron tube 16. The grid-filament circuit comprises a grid 17 and a filament 18 heated by means of a suitable battery 19. The grid-filament circuit of the amplifier tube 16 is tuned to 70 resonance at the usual operating frequency with the capacitance of the tube and the winding. This means that the greatest possible number of turns are used in the inductance 15. Since the inductance 15 is the secondary of the intertube transformer in which the inductance 14 is the primary, the greatest possible number of turns are employed in the secondary. This will give the maximum possible amplification.

The plate circuit of the amplifier tube 16 has a plate element 22, a plate battery 23 and an inductance 24, which latter operates as the primary of an intertube transformer. The inductance 24 corresponds, in design and function, exactly to the inductance 14 of the plate circuit of the tube 7. Inductively coupled, through iron, to the inductance 24, forming the primary of the intertube transformer, is an inductance 25, located in the grid-filament circuit of an amplifier tube 26, having a grid element 27 and a filament element 28. The filament 28 is heated by a suitable "A" battery 29. The grid-filament circuit of the amplifier tube 26 is tuned to be resonant to the operating frequency and, in every respect, corresponds, in function and design, to the grid-filament circuit of the electron tube 16. The plate circuit of the electron tube 26 comprises a plate element 32, a "B" battery 33 and a pair of telephone receivers 34 through which amplified signals may be caught.

The connection of the amplifier tubes 5, 16, and 26 is in cascade and produces a greater amplification than is possible with the use of one tube. This is a customary expedient in the art, and my invention does not lie in cascading tubes but in the peculiar use of transformer secondary circuits; i. e., grid-filament circuits, tuned to resonance at the customary operating frequency to obtain a maximum amplification.

In the circuit shown in Fig. 2, the dotted lines indicate a capacitance C in parallel with the inductance Z_p of the primary of the transformer. In this equivalent circuit, the capacitance C represents the equivalent effect of the grid-filament circuit of the amplifier tube, which, with inductance L_p , is resonant at the average operating frequency. This will cause the circuit Z_p-C to be a tuned parallel circuit.

The characteristics of a tuned parallel circuit will be evident from a study of the curves shown in Fig. 3. In such circuit, the ordinates are used to plot the current and, the abscissa the frequency. It is well known that the current flowing through a reactance is equal to E divided by the value of the re-

actance. In the case of capacitance, "I," therefore, equals $E2\pi f/C$. In the case of inductance, "I" equals

$$\frac{E}{2\pi fL}.$$

Since the current through capacitance leads ninety degrees in phase and the current through inductance lags ninety degrees 10 in phase, the resultant current through capacitance and inductance in parallel equals the difference between the values represented by the two curves. This gives us the curve C.

At resonant frequency f , the current value 15 is zero for, at that frequency, the capacitance and inductance in parallel theoretically act as infinite resistance. This is true upon the assumption that resistance plays no part in the circuit. Since such is never the case, the 20 curve, in which impedance is the ordinate and frequency the abscissa, is represented by D in Fig. 4, in which the value of the impedance, at the resonant frequency, is shown as relatively high though not infinite.

25 In the past, the trouble with using a secondary resonant to average operating frequency in transformer action between tubes has been that the impedance in the primary circuit of the transformer changed too much 30 for use in practice, particularly in telephony, around the resonant frequency. But since, as I have before stated, I make my impedance in the primary of relatively high value initially, I obtain a considerable flattening 35 of the impedance curve at resonance. This is illustrated by the dotted line, curve G of Fig. 4, in which Z_p represents the impedance at the greatest distance from resonance. Therefore, the resonant point is sufficiently 40 well obscured to produce an impedance which is constant enough with variable frequency to give satisfactory results in telephony.

45 Thus, I am able to use a transformer coupling between vacuum tubes in which the secondary; i. e., the grid-filament circuit, contains the necessary number of turns so that it is tuned to resonance and, therefore, comprises the maximum number of turns. 50 Since the ratio of the number of turns in a secondary of a transformer to the number of turns in the primary determines the amplification, by employing a tuned secondary with the maximum possible number of turns, 55 I can obtain a greater amplification than has yet been achieved. It is necessary to use a winding which has a low distributed capacity, the lower the capacity the greater the number of turns it is possible to use.

60 In operation, radio oscillations, having been caught by the antenna circuit, induce corresponding oscillations in the inductance 4, by reason of the inductive coupling between the inductance 2 and the inductance 4.

65 By suitable adjustment of the variable ca-

pacitance 6, the grid circuit of the vacuum tube 5 may be tuned to any desired frequency. The "A" battery 11 applies a suitable degree of heat to the filament 10 of the electron tube to cause it to emit electrons, 70 and the potential of the grid 7 affects the flow of electrons between the filament 10 and the plate element 12 of the electron tube, in accordance with the received oscillations. These oscillations are amplified in the plate-filament circuit of the tube and produce amplified oscillations in the inductance 14, 75 which is the primary of an intertube transformer.

The value of the inductance 14 is such that 80 a comparatively large value of the voltage in the circuit acts across this inductance. Inductively coupled through iron, is the secondary 15 of the intertube transformer that lies in the grid-filament circuit of the electron tube 16. The grid-filament circuit of the electron tube 16 is tuned to resonance with the average operating frequency. This means that the maximum possible number of turns are used in the inductance 15. The inductance 14, forming the primary, is of 85 large enough value, so that the resonant point is sufficiently well obscured to produce a sufficiently constant impedance in the primary to give satisfactory results in 90 telephony.

The primary 14 is, however, not of too large value for the reason that the amplification of the intertube transformer depends upon the ratio of the number of turns in the 100 secondary to the number of turns in the primary. The grid 17 of the electron tube 16 which lies in the grid-filament circuit of that tube has an amplified potential applied to it. This potential, modulated in accordance 105 with the received signals, controls the electron flow between filament element 18 and plate element 22 of the electron tube 16. This, in turn, produces amplified oscillations in the plate circuit of the electron tube 16 110 which comprises the inductance 24. The inductance 24 is similar, in design and function, to the inductance 14 and forms the primary of an intertube transformer the secondary of which is the inductance 25. The 115 inductance 25 lies in the grid-filament circuit of the electron tube 26 and this circuit is tuned to resonance at the average operating frequency.

The grid-filament circuit of the electron tube 26 operates and is designed in exactly the same manner as the grid-filament circuit of the electron tube 16. The tubes 16 and 26 are cascaded for the purpose of furnishing additional amplification. Within the filament-plate circuit of the electron tube 26 are located telephone receivers 34 to catch the amplified signals.

While I have illustrated my system of 130 intertube coupling as applied to a receiving

system, it is to be distinctly understood that it may be applied to a sending system, and that I have shown a receiving system solely for the purpose of explanation and to make clear the principles of operation of my invention.

By my form of intertube coupling, I am enabled to obtain the maximum voltage amplification possible. The amplification in 10 transformers depends upon the ratio of the number of turns of the primary to the number of turns of the secondary. The greater the number of turns in the secondary the greater will be the amplification of potential. 15 The maximum number of turns practically possible in the secondary is obtained when the distributed capacity of the secondary circuit; i. e., the grid-filament circuit, is tuned to resonance with the inductance of the 20 winding at the average operating frequency. My system has the peculiar advantage that the maximum amplification possible is obtained by reason of the use of a secondary circuit in intertube transformers that shall 25 be resonant to operating frequencies.

Since I have not shown and described all of the possible embodiments of my invention that will be apparent to those skilled in the art, I desire that my invention be limited 30 only by the appended claims and the showing of the prior art.

I claim as my invention:

1. In combination, two vacuum tubes and a transformer, the primary of said transformer being connected to the output of the 35 first tube and the secondary to the input of the second tube, the inductance of said primary being large relative to the output impedance of the first tube and smaller than the inductance of the secondary, the inductance of said secondary being such that, with the distributed capacity thereof and the input capacity of the second tube, it forms a circuit 40 resonant to the average frequency of the currents for which the combination is intended.

2. In an amplifying system, means for supplying currents of frequencies comprised within a predetermined frequency band, a pair of vacuum tubes and a transformer between the tubes, the primary of said transformer being connected in the output circuit of the first of said tubes and having sufficient inductance to constitute it the major part of the impedance of said output circuit both 45 within and without said first tube, the secondary of said transformer being connected in the input circuit of the second tube and having sufficient inductance to render said input circuit resonant at the average frequency of said frequency band.

3. In an amplifying system, means for supplying currents of frequencies comprised within a predetermined frequency band, a pair of vacuum tubes and a closely coupled 50 transformer between the tubes, the primary

of said transformer being connected in the output circuit of the first of said tubes and having sufficient inductance to constitute it the major part of the impedance of said output circuit both within and without said first 70 tube, the secondary of said transformer being connected in the input circuit of the second tube and having sufficient inductance to render said input circuit resonant at the average frequency of said frequency band. 75

4. In an amplifying system means for supplying currents of frequencies comprised within a predetermined frequency band, a pair of vacuum tubes and a closely coupled transformer between the tubes, the primary 80 of said transformer being connected in the output circuit of the first of said tubes and having sufficient inductance to render the transformer of sufficiently broad tuning to transmit effectively variations of the frequency corresponding to modulation and to constitute it the major part of the impedance of said output circuit both within and without said first tube, the secondary of said transformer being connected in the input 85 circuit of the second tube and having sufficient inductance to render said input circuit resonant at the average frequency of said frequency band.

5. In an amplifying system, means for 90 supplying currents of frequencies comprised within a predetermined frequency band, a pair of vacuum tubes and a closely coupled transformer between the tubes, the primary of said transformer being connected in the output circuit of the first of said tubes and having sufficient inductance to so obscure the 95 resonance point of the transformer that it will not produce perceptible distortion and to constitute it the major part of the impedance of said output circuit both within and without said first tube, the secondary of said transformer being connected in the input 100 circuit of the second tube and having sufficient inductance to render said input circuit resonant at the average frequency of the 105 said frequency band.

6. In combination, two vacuum tubes and a closely coupled transformer, the primary of said transformer being connected to the 110 output of the first tube and the secondary to the input of the second tube, the inductance of said secondary being such that, with the distributed capacity thereof and the input capacity of the second tube, it forms a circuit 115 resonant to the average frequency of the currents for which the combination is intended, whereby the sharpness of the tuning of the combination is determined by the amount of inductance in the primary of said 120 transformer.

In testimony whereof, I have hereunto 125 subscribed my name this 26 day of February, 1921.

MAX C. BATSEL.

CERTIFICATE OF CORRECTION.

Patent No. 1,664,239.

Granted March 27, 1928, to

MAX C. BATSEL.

It is hereby certified that the above numbered patent was erroneously issued to the inventor said "Batsel", whereas said patent should have been issued to "Radio Corporation of America", of New York, N. Y., a corporation of Delaware, said corporation being assignee of the entire interest in said invention, as shown by the records of assignments in this office; and that the said Letters Patent should be read with this correction therein that the same may conform to the record of the case in the Patent Office.

Signed and sealed this 19th day of June, A. D. 1928.

M. J. Moore,
